UNITED STATES PATENT OFFICE.

OSCAR WOODWARD, OF MONTCLAIR, NEW JERSEY, ASSIGNOR TO UNION TYPEWRITER COMPANY, OF JERSEY CITY, NEW JERSEY, A CORPORATION OF NEW JERSEY.

TYPE-WRITING MACHINE.

1,000,476.

Specification of Letters Patent. Patented Aug. 15, 1911.

Application filed May 19, 1909. Serial No. 496,977.

To all whom it may concern:

Be it known that I, OSCAR WOODWARD, citizen of the United States, and resident of Montclair, in the county of Essex and State of New Jersey, have invented certain new and useful Improvements in Type-Writing Machines, of which the following is a specification.

My invention relates to typewriting machines and more particularly to the construction of hangers for said machines, and to means for securing said hangers in place. In the present instance the hangers are shown as type bar hangers.

The main object of the invention is to provide a simple and efficient construction of the character specified in which the individual hangers may be readily mounted in place in or removed from the machine.

To the above and other ends which will hereinafter appear, my invention consists in the features of construction, arrangements of parts and combinations of devices to be hereinafter described and claimed.

In the accompanying drawings in which like reference characters indicate corresponding parts in the various views, Figure 1 is a skeletonized side view, partly in section, showing a type action and a diagrammatic illustration of a platen with the feature of my invention embodied therein. Fig. 2 is an enlarged detail fragmentary vertical sectional view of one form of construction embodying my invention. Figs. 3 and 4 are enlarged detail perspective views of a pair of coöperating devices by which the hanger is secured in place on the segment. Fig. 5 is an enlarged detail front view showing a hanger mounted in place on the segment. Fig. 6 is an enlarged detail side elevation, partly in section, of a modified form of coöperating connecting devices for securing a hanger in place. Fig. 7 is an enlarged end view of one of the connecting members shown in Fig. 6. Fig. 8 is an enlarged detail perspective view of the same. Fig. 9 is a side elevation of a modified form of nut employed in connection with the companion securing member shown in Fig. 6.

Fig. 10 is an end view of the same. Fig. 11 is a view corresponding to Fig. 2 but showing a still further modification of the securing means. Figs. 12 and 13 are enlarged detail perspective views of the securing means disclosed in Fig. 11.

A key lever 1 is fulcrumed at 2 to the frame 3 of the machine and is connected to a link 4, the upper end of which is connected to an angular lever 5 pivoted at 6 to the frame of the machine. A rearwardly extending link 7 is connected at its front end to the upright arm of the angular lever and at the rear end to a type bar 8 pivoted at 9 on trunnion-like pivots received between arms 10 of a bifurcated type bar hanger. The outline of the type bar hanger in side elevation is shown in Fig. 1, whereas the shape of the hanger as viewed from the front of the machine is shown in Fig. 5 and the hanger, as presented in this latter view, is substantially U-shaped in cross section, the arms 10 of the hanger being united at the looped portion thereof as at 11. The construction is such that the stem or shank 12 of the hanger is formed of two parallel side plates which are united by a screw 13 passing freely through an opening in one of the arms of the hanger and engaging at its threaded end in a tapped opening in the other hanger arm so that an adjustment of the hanger arms may be effected.

In the form of construction shown in Figs. 1, 2 and 3 a T-shaped head or securing member 14 is provided with a reduced cylindrical stem 15 which extends through an opening 16 in a support or type bar segment 17 and the rear threaded end 18 of the stem coöperates with an open-ended nut 19 having a screw-driver nick 20 therein. The T-shaped head 14 constituting one of the securing members, has the stem 21 thereof of a thickness which corresponds substantially to the space between the arms of the stem or shank of the hanger, whereas the cross piece 22 of the T-shaped head is adapted to bear on the forward edges of the stem or shank of the hanger and to force the stem into contact with the front face of the type bar segment and thus bind the hanger in place when the nut 19 is tightened. It will be understood that by providing a construction such as that shown in which flat sides 23 of the T-shaped head coöperate with the hanger arms the securing member is prevented from turning relatively to the hanger so that a tightening of the nut 19 may be readily effected, while the hanger is held in place, without turning the securing member 14. The construction shown in Figs. 6, 7, 8, 9 and 10 is essentially the same as that shown in Fig. 11.

in the preceding figures except that the stem 21^a of the securing member 14^a is of the same thickness throughout its length and is received in an opening that corresponds to the 5 greatest diameter of the stem. The flattened sides 23^a in this construction coöperate with the hanger arms in the same manner as in the previously described construction. A nut 19^a with a closed head, as shown in Fig. 10 6, may be employed to coöperate with the securing member 14^a or an open-ended nut 19^b, such as that shown in Figs. 9 and 10, may be employed in connection with the companion securing member. In the construction 15 shown in Figs. 11, 12 and 13 the securing head 14^b is similar to that shown in Fig. 4 except that there is a tapped opening 24 therein to receive the threaded end 25 of a headed screw 26. As will be seen from an inspection of Fig. 11 this screw is passed 20 through an opening 27 in the segment from the rear thereof and engages at its forward threaded end in the tapped opening in the T-shaped securing head 14^b, so as to bind the type bar hanger between the securing 25 head and segment and thus secure the hanger in place. In all of these constructions the T-shaped head or securing member coöperates with the hanger in essentially the 30 same manner and a simple and convenient securing means is provided by which the individual hangers may be readily mounted in place or detached from the machine and by which the securing head is held against turning movement with reference to the type 35 bar hanger, while the other companion or co-operating threaded member is screwed in place or unscrewed to afford an attachment or detachment of the parts. Moreover the 40 constructions are such that the securing means for each hanger occupy no greater widthwise space than the hanger itself and the nuts or securing members at the rear of the segment, in some instances, are even 45 of less width than the width of the hangers, so that a close arrangement of the hangers may be effected. Furthermore, it will be seen that in each instance access may be had to the securing means from the rear of the 50 segment, which in a front-strike typewriting machine of the character shown in Fig. 1, wherein the actuating devices are in the front of the type bar segment, this construction affords more ready access to the securing 55 means for the hanger than would be the case if the securing screws or bolts were presented for adjustment from the front of the machine.

What I claim as new and desire to secure 60 by Letters Patent, is:—

1. In a typewriting machine, the combination of a type bar, a hanger having a substantially U-shaped shank, a segment having a flat face against which the stem of the hanger bears, a T-shaped head, the cross-piece of which bears on the U-shaped shank of the hanger to hold the hanger in place and the stem of the T-shaped head having a thickness that corresponds substantially to the distance between the arms of the shank 65 of said hanger, said stem having flattened faces that coöperate with the hanger to prevent a relative turning movement between the T-shaped head and the hanger, but affording a turning movement of the head 70 relatively to the segment, and an independent securing member that has a threaded connection with said head.

2. In a typewriting machine, the combination of a bifurcated hanger, a support therefor, said support having an opening therethrough and a flat face against which the stem of the hanger bears, a T-shaped securing head adapted to be turned relatively to the segment, the stem of the T-shaped head 80 passing through the opening formed by the bifurcation in the hanger and having a positive connection with the hanger to prevent a relative turning movement between the two and the cross-piece of the T-shaped head 85 bearing against the hanger to hold it in place, a second securing member, one of said securing members passing through the opening in said support, and a threaded connection 90 between the two securing members. 95

3. In a typewriting machine, the combination of a perforated segment, a U-shaped hanger bearing against the front face thereof, a type bar pivotally connected to said hanger, a threaded securing-member adapted to turn relatively to the segment and having a shank with squared sides fitting closely between the arms of said U-shaped hanger to prevent a relative turning between the securing member and hanger, said securing 100 member also having overhanging lips which bear upon the outer edges of the said hanger arms, and a companion threaded securing-member engaging the said first mentioned member and also bearing against the rear 105 face of the said segment. 110

Signed at the borough of Manhattan, city of New York, in the county of New York, and State of New York, this 17th day of May, A. D. 1909.

OSCAR WOODWARD.
